E. C. ZISTERER.
LEAF SPRING FOR VEHICLES.
APPLICATION FILED JULY 6, 1915.

1,184,910

Patented May 30, 1916.

Inventor:

Emil C. Zisterer
v/ Charles O. Showey,
his Atty.

UNITED STATES PATENT OFFICE.

EMIL C. ZISTERER, OF CHICAGO, ILLINOIS.

LEAF-SPRING FOR VEHICLES.

1,184,910.

Specification of Letters Patent. Patented May 30, 1916.

Application filed July 6, 1915. Serial No. 38,046.

To all whom it may concern:

Be it known that I, EMIL C. ZISTERER, a citizen of the United States, and a resident of Chicago, county of Cook, and State of Illinois, have invented certain new and useful Improvements in Leaf-Springs for Vehicles, of which the following is declared to be a full, clear, and exact description.

This invention relates to leaf springs for vehicles, and its object is to provide means whereby the several leaves of the spring may be lubricated without the necessity of separating said leaves for the insertion of the lubricant.

It is well known that the task of lubricating leaf springs of vehicles, particularly, of automobiles, is an irksome and tedious one, and that unless the springs are lubricated they become noisy, friction develops and the car does not ride so easily as with well lubricated springs.

The present invention consists in the provision of intercommunicating conduits formed in one or more contiguous faces in the leaves of the spring, and means for supplying a lubricant to said conduits.

The invention further consists in the novel features hereinafter set forth and defined in the claims.

The invention is clearly illustrated in the drawing furnished herewith, of which:

Figure 1 is a longitudinal section through the lower spring of an elliptical leaf spring; Fig. 2 is a face view of the lowermost leaf of the spring looking in the direction of the arrow, 2, in Fig. 1; Fig. 3 is a face view of the leaf immediately above the lowermost leaf, looking in the direction indicated by the arrow, 3, in Fig. 1; Fig. 4 is a face view, 40 of the leaf located immediately above the one shown in Fig. 3, looking in the direction of the arrow, 3, in Fig. 1; Fig. 5 is a detail vertical cross section taken on the line 5-5 of Fig. 1; and Fig. 6 is a detail longitudinal section of fragments of two leaves.

In the embodiment of the invention illustrated in the drawing, 10 designates a leaf spring which may comprise the lower spring of an elliptical leaf spring, and in accordance with the usual practice comprises a plurality of individual leaves, 11, 12, 13, 14, 15, 16 and 17, arranged one above the other, the several leaves increasing in length as they progress upwardly. The uppermost leaf, 17, is formed at its ends with eyes or loops, 18,

for the reception of bolts which connect the lower spring with the upper spring, or with the frame of the vehicle supported by the lower spring, as is common with springs of this type. The middle portion of the spring is attached to the axle of the vehicle by U-bolts, a, as is well understood by those familiar with the art, and all the levers are firmly clamped together by said U-bolts. 65 Besides this the weight of the vehicle upon the upper ends of the spring serves to hold the contiguous leaves in firm contact with each other.

In carrying out my invention I provide 70 conduits, preferably in the lower faces of all of the leaves, except the lowermost one, said conduits running from a point near the middle of each leaf to a point near each end. Said conduits are conveniently provided by 75 forming lengthwise extending shallow grooves, 19, in the lower faces of the leaves, and, if desired, the outer ends of said grooves may terminate in widely spreading, shallow 80 hollows, 20, for holding a quantity of lubricant.

It is understood that there are two sets of conduits, one set located near each end of the spring, and the several conduits of each set communicate with each other 85 through apertures, 21, formed in the body of each leaf at some point in the groove thereof, thus providing a continuous channel or conduit in the contiguous faces of the leaves, through which channel or conduit a 90 lubricant may be forced from some point outside of the spring.

In the form shown the lowermost leaf, 11, is provided in its upper face with a conduit or groove, 19^a, extending between the apertures, 21, 21, of the leaf above and has an aperture, 22, extending out from said groove and communicating with a grease cup, or other lubricant reservoir, 23, secured to and projecting down from the lower face of said leaf, 11. Said grease cup may be of any well known form, having a plunger or cap, 24, which may be screwed down to force a suitable, semi-solid lubricant between the leaves of the spring. In the lower face of the 105 leaf, 12, the conduit, 19^a, extends from a point near one end of the leaf to a point near the other end thereof and is complementary to the groove, 19^a, in the lowermost leaf; it communicates with the grooves in 110 the leaf above, through the apertures, 21, as clearly indicated in Fig. 1 of the drawing.

If desired, the grooves, 19, may have lateral extensions, 19^b, as shown in Fig. 4, to conduct the lubricant toward the side edges of the leaf. Short grooves, 19^a, may be formed in the upper faces of the intermediate leaves, running from the aperture of one leaf to the one in the leaf above, thus providing round grooves at those places.

- 10 10 In use a suitable spring lubricant, such as a mixture of hard grease and graphite, is placed in the cup, 23, and the plunger or cap screwed down, thereby forcing the grease through the intercommunicating conduits at both ends of the spring, and when all of the conduits have been filled with lubricant, then by applying still greater force on the lubricant in the cup, the lubricant in the grooves is forced out between 15 the contiguous faces of the leaves of the spring.
- 20 20 From the above it is perfectly evident that a leaf spring equipped with a lubricating means as herein described, may be kept in good working condition at all 25 times, and that the laborious and time-consuming task of lubricating the spring is eliminated, and that when the supply of lubricant in the grease cup is exhausted, 30 the cup may be readily filled with a fresh supply, and the cap or plunger turned down to supply the spring with fresh lubricant. It is to be understood that the upper spring 35 of an elliptical leaf spring may be lubricated in the same manner as the lower spring.

More or less variation of the exact details of construction is possible, without depart-

ing from the spirit of my invention, and I desire, therefore, not to limit myself to 40 the exact form of construction shown and described, but intend in the following claims to point out all of the invention disclosed herein.

I claim as new and desire to secure by 45 Letters Patent:

1. A leaf spring for vehicles, comprising a plurality of superimposed spring leaves, the lower faces of the leaves, above the lowermost one, having lengthwise extending 50 grooves formed therein and extending throughout the greater portion of their length, and the upper faces of the leaves, intermediate the top and bottom leaves, having lengthwise extending short grooves 55 formed therein and registering with the long grooves near their outer ends, the short grooves of each leaf communicating with the long groove below through an aperture, thereby forming an intercommunicating 60 series of lubricant receiving conduits, and a cup for receiving lubricant, communicating with said intercommunicating conduits.

2. A leaf spring for vehicles comprising 65 a plurality of superimposed leaf springs, the lower faces of the leaves above the lowermost one having lengthwise extending grooves formed therein, apertures in said leaves forming communication between the 70 grooves of one leaf and that of the adjacent ones, short grooves in the upper faces extending between the aperture of each leaf and the one on the adjacent leaf, and a lubricant reservoir opening to said grooves. 75

EMIL C. ZISTERER.
